Patented Oct. 10, 1922.

Inventor
Max Spillmann
By his Attorney
Philip Jacques Lee Kennedy

UNITED STATES PATENT OFFICE.

MAX SPILLMANN, OF RICHFIELD, NEW JERSEY, ASSIGNOR TO WORTHINGTON PUMP
AND MACHINERY CORPORATION, A CORPORATION OF VIRGINIA.

TURBINE-DRIVEN CENTRIFUGAL PUMP.

Application filed November 13, 1920. Serial No. 423,888.

To all whom it may concern:

Be it known that I, MAX SPILLMANN, a citizen of Switzerland, residing at Richfield, county of Passaic, and State of New Jersey, 5 have invented certain new and useful Improvements in Turbine-Driven Centrifugal Pumps, fully described and represented in the following specification and the accompanying drawings, forming a part of the 10 same.

This invention relates to improvements in centrifugal pumps, and especially to pumps of this type driven directly by steam turbines, the turbine rotor and pump impeller 15 being mounted upon a single shaft.

The object of this invention is to provide a cheap, compact and efficient centrifugal pump having an increased capacity, thereby requiring fewer stages, and so arranged as to allow the use of a lighter shaft. 20

In the accompanying drawing, forming a part of this specification, there is shown by way of illustration a side elevation of a two stage centrifugal pump, with its first 25 stage shown in section, embodying all the features of the invention in their preferred form, and this construction will now be described in detail and the features forming the invention then specifically pointed out 30 in the claims.

Referring to the drawing, this steam turbine driven centrifugal pump comprises preferably a turbine section A and a pump section B provided with abutting flanges C 35 secured together in any suitable manner and supporting members D, E forming a support therefor.

Turbine section A encloses a suitable rotor and is provided with the usual steam 40 inlet connection F and an exhaust connection G.

The pump section B comprises two stages H and I connected by connection J. In order to obtain increased capacity I prefer- 45 ably provide the first stage H with an over-hung impeller K to which the fluid passes from inlet connection L, the second stage I

being of any suitable type and provided with discharge connection M. I am enabled to use a lighter shaft by providing a 50 bearing P situated between the two stages of the pump and preferably supported on connection J by standard Q. When the pump is used in a direct driven unit as shown, I may advantageously provide a sec- 55 ond bearing O for the shaft M outside and beyond the turbine A.

By means of this arrangement having an overhung first stage impeller, I am enabled to obtain a greatly increased capacity and pressure thereby requiring fewer stages, and by the location of the bearings a lighter shaft can be used in a unit having relatively 60 smaller dimensions.

What I claim is:

1. A centrifugal pump unit comprising 65 an overhung first stage impeller, a second stage adjacent to the first stage, a shaft common to both stages, driving means for said shaft arranged with the second stage 70 between it and the first stage, and a bearing for the shaft between the first and second stages.

2. In a steam turbine driven centrifugal pump the combination with the turbine and 75 its rotor, of a two stage centrifugal pump, a shaft common to the rotor and pump impellers, and two bearings for the shaft mounted one at the turbine end and outside the turbine and the other between the 80 two stages of the pump.

3. In a steam turbine driven centrifugal pump the combination with the turbine and its rotor, of a two stage centrifugal pump, an overhung impeller on the first stage, a 85 shaft common to the rotor and pump impellers and two bearings for the shaft mounted one at the turbine end and outside the turbine and the other between the two stages of the pump.

In testimony whereof, I have hereunto 90 set my hand.

MAX SPILLMANN.
